UNITED STATES PATENT OFFICE.

LAZARD KAHN, OF HAMILTON, OHIO, ASSIGNOR TO F. & L. KAHN & BROS.,
OF SAME PLACE.

DESIGN FOR A GAS-STOVE.

SPECIFICATION forming part of Design No. 21,311, dated January 26, 1892.

Application filed December 31, 1891. Serial No. 416,734. Term of patent 7 years.

To all whom it may concern:

Be it known that I, LAZARD KAHN, a citizen of the United States, residing at Hamilton, Butler county, Ohio, have invented and produced a new and original Design for Gas-Heating Stoves, (Case A,) of which the following is a specification, reference being had to the accompanying drawing, forming part thereof.

10 The drawing is a front perspective view of a gas-heating stove, showing my design.

In the drawing, A indicates the cylindrical body of the stove; B, the band of ornamental perforations encircling the upper portion of the body; C, a perforated crown at the top of the body; D, a large rectangular opening at the base of the body, exposing horizontal cor-

rugations to the rear of the opening; E, the base of the stove, with its rear portion conforming to the circular plan of the body and at its front projecting forward of the body and extended sideways to greater width than the diameter of the body; F, an ornamental escutcheon imposed against the front of the body over the opening B, and G legs projecting downwardly and outwardly from the extreme side portions of the base E.

I claim—

The design for a gas-heating stove, as herein described and shown.

LAZARD KAHN.
